[57] CLAIM

The ornamental design for an internal-combustion engine hood, as shown and described.

DESCRIPTION

FIG. 1 is a left-front perspective view of an internal-combustion engine hood showing my new design;

FIG. 2 is a right-front perspective view thereof;

FIG. 3 is a left side view thereof;

FIG. 4 is a right side view thereof;

FIG. 5 is a front view thereof;

FIG. 6 is a rear view thereof; and,

FIG. 7 is a top plan view thereof.

The remaining portion of the engine shown in dotted lines, forms no part of claimed design.
